UNITED STATES PATENT OFFICE.

JOHN C. HALL AND CLEMENCE A. MAHLE, OF CORRY, PENNSYLVANIA.

BRUSH-BLOCK-BORING MACHINE.

SPECIFICATION forming part of Letters Patent No. 284,128, dated August 28, 1883.

Application filed March 27, 1883. (Model.)

To all whom it may concern:

Be it known that we, JOHN C. HALL and CLEMENCE A. MAHLE, of the city of Corry, in the county of Erie and State of Pennsylvania, 5 have invented certain new and useful Improvements in Brush-Block-Boring Machines; and we do hereby declare the following to be a full, clear, and exact description of the invention, such as will enable others skilled in the 10 art to which it pertains to make and use it, reference being had to the accompanying drawings, which form part of this specification.

Our invention relates to an improvement in 15 brush-block-boring machines; and it consists in the combination of the driving-shaft, provided with a suitable pulley, with the shaft for the carrier-plate, which passes eccentrically through it, so as to give the necessary motion to the driving-plate, and at the same time 20 form a long bearing for the shaft which operates the plate, as will be more fully described hereinafter.

The object of our invention is to make the 25 driving-shaft operate the shaft which carries the carrier-plate, and thus do away with the usual crank or wrist which has heretofore been used, and to give the shaft which carries the carrier-plate a long bearing, so as to prevent it from heating.

Figure 1 is a side elevation of our invention complete. Fig. 2 is an end view of the same.

A represents a frame of any suitable shape, size, or construction that may be preferred, 35 and which has the bearings B formed upon its top for the driving-shaft C. This driving-shaft will preferably be provided with a driving-pulley, D, and a balance-wheel, E, upon its inner end, as shown. Bored through this 40 shaft, to one side of its center, is a suitable hole or opening, in which is placed the shaft G, which has the carrier-plate H attached to its

inner end. As the driving-shaft is made to revolve, this shaft G is carried around with it and through a circle just large enough to give 45 the carrier-plate its required motion. By this construction a long bearing is formed for the shaft G. The ordinary crank which has heretofore been used is done away with, and the heating of the operating parts is prevented. 50 The bearing for the boring-rods is held in a suitable frame, and at one end of the frame A is placed a suitable slide, I, upon which the brush-block is to be placed, and this slide is connected to a spring-actuated lever, J. This 55 lever J is operated in turn by means of the crank-lever O, by means of which the brush-block is forced against the revolving rods.

In the patent granted to us December 17, 1878, a single shaft having a crank formed on 60 one end for moving the disk H is shown; but the trouble with this construction is that the crank forms too long a bearing and is apt to become bent. By inclosing the shaft G, as is here shown, it can never become bent, and 65 when worn out the shaft has only to be removed and another one inserted.

Having thus described our invention, we claim—

In a brush-block-boring machine, the combination of the driving-shaft with the shaft which carries the carrier-plate, the carrier-plate shaft being passed through the driving-shaft to one side of its center, substantially as described. 70

In testimony whereof we affix our signatures in presence of two witnesses.

JOHN C. HALL.
CLEMENCE A. MAHLE.
